FREQUENCY DISCRIMINATING NETWORK

Winfield R. Koch, Haddonfield, N. J., assignor
to Radio Corporation of America, a corpora-
tion of Delaware

Application September 30, 1937, Serial No. 166,495

10 Claims. (Cl. 250—20)

This invention relates to frequency discriminating networks for radio signaling systems including automatic frequency and volume controlling means, and has for its principal object the provision of an improved apparatus and method of operation whereby automatic control of the frequency and signal volume in such systems may be effected without the expense and disadvantages heretofore incident to the construction and operation of such devices.

Automatic frequency control circuits heretofore available have usually included a center tapped winding, separate primary and secondary windings, a blocking condenser and choke coil, a separate detector circuit, a tube capable of performing a plurality of functions or combinations of certain of these features. Such circuits are expensive both because of the accurate center tapping required and because of the choke coil involved and are not altogether satisfactory for the reason that the diode used for securing audio frequency potentials has impressed on it the signal potentials from both the primary and the secondary of the coupling transformer. Under these circumstances, not only is the full selectivity of the transformer not utilized but the voltage impressed on the diode varies throughout the desired frequency band, or channel, instead of remaining substantially constant.

In accordance with the present invention, these difficulties are minimized or avoided by the use of means including a pair of diode tube elements so interconnected as (1) to detect the modulation or audio component of the signal, (2) to provide suitable automatic volume control potentials, and (3) to provide suitable automatic frequency control potentials. More specifically stated, the modulated signal or intermediate frequency impulses are supplied through a coupling transformer to one diode which detects the modulation component and affords one component of a resultant unidirectional voltage which is utilized in effecting automatic control of the amplitude of the carrier frequency. Another diode is subjected to the resultant of the coupling transformer primary and secondary voltages for producing another unidirectional potential which varies with change in the phase relation between the primary and secondary voltages, and which is combined with the substantially constant unidirectional component of the detected potential for automatically regulating the carrier frequency. For the automatic volume control potential derived from the output of the signal detector, suitable filters are provided to exclude

the carrier and modulation frequency impulses from the automatic control circuits. As will appear, this inventive concept is capable of embodiment in various circuits some of which are hereinafter described in considerable detail.

The invention will be better understood from the following description when considered in connection with the accompanying drawings and its scope is indicated by the appended claims.

Referring to the drawings,

Figure 1 is a wiring diagram of a preferred embodiment of the invention wherein the automatic frequency control potential is derived from series-connected resistors.

Figures 2 to 4 are explanatory diagrams relating to the operation of the invention.

Figure 5 illustrates the application of the invention to a tuned radio receiver including grounded rotor condensers, the automatic frequency potential being in this case derived from a bridge network instead of series-connected resistors.

Figure 6 illustrates a modification differing from those of Figs. 1 and 5 in that substantially constant component of the automatic frequency control potential is derived from the transformer primary instead of the transformer secondary, thus permitting the following tube to function either as a detector or amplifier.

Figure 7 illustrates a modification which differs from the previous modifications in that the automatic frequency control potential derived from the network has the opposite polarity at any frequency from that derived from the network in Fig. 1. This is desirable for some types of frequency control means.

Figure 8 exemplifies a modification in which only part of the primary voltage is utilized, and

Figure 9 illustrates a modification including a voltage doubler detector arranged to produce the automatic frequency control potential through a bridge network.

The circuit of Fig. 1 includes an input transformer 10, an intermediate frequency amplifier tube 11, a coupling transformer 12, a detector 13, 45 a coupling resistor 14 and an audio frequency amplifier tube 15. As hereinafter referred to, the relative frequency response between the primary and secondary voltages within the pass band of the transformer 12, which is of the tuned type, is shown in Figure 2. Connected between the primary winding 16 and the secondary winding 17 of the coupling transformer 12 is a circuit including capacitors 18 and 19 and a diode 20 which is shunted by a pair of resistors 21 and 22. Auto- 50 55

matic frequency control potential dependent on the unidirectional potential drops of the resistors 14 and 22 is applied to the lead 23, impulses of audio frequency being excluded from this lead 5 by filter means such as the capacitor 19 and a resistor 24 interposed between the resistors 14 and 22. Impulses of both radio and audio frequencies are further excluded from this lead by the capacitor-resistor filter 25-26. The capacitors 10 tors 18 and 19 afford direct current isolation for the diode 20, thus permitting the series connection of the resistors 14 and 22.

Automatic volume control potential is applied to a lead 27 from the output of the detector 13 15 through a resistor 28 which functions with a capacity 29 to form a filter whereby audio and radio frequency impulses are excluded from this automatic volume control lead 27. The resistor 24 also prevents radio frequency impulses from 20 getting into the automatic volume control circuit.

The operation of the circuit of Fig. 1 will be 25 readily understood. Where exact tuning is in the center of the frequency band, the primary and secondary voltages of the transformer 12 are disposed in phase by approximately 90 degrees for the reason that they provide two coupled circuits, tuned to the same frequency. The resistors 21 and 22 on which the resultant of the primary and secondary voltages is impressed are so proportioned that, at exact tuning, the potential drop of resistor 22 is equal to and opposed to that of resistor 14. Under these conditions, the automatic frequency control potential is zero at exact tuning. Since the unidirectional potential drop 30 of the resistor 14, that is, the rectified secondary voltage, is substantially independent of change in frequency in the region of exact tuning due to the band-pass characteristic of the transformer 12 that is, band pass tuning response in a relatively narrow band about the mean frequency of 460 kc. as indicated by the response curves of Figure 2, and the drop of resistor 22 changes rapidly with change in frequency, there is applied to the automatic frequency control lead 23 a potential which 35 is of one polarity when the frequency is too high and is of the opposite polarity when the frequency is too low. Thus, the automatic frequency control potential may be positive when the frequency is too low and negative when the frequency is too high or vice versa, according to the frequency adjusting element to be controlled, and depending on the direction of the coupling between the primary 16 and the secondary 17 of the coupling transformer.

The rectified primary or secondary voltage is balanced against the vector sum of the primary and secondary voltages rectified thereby to produce a composite output potential. At resonance the drop in resistors 22 and 14 are equal and the 40 automatic frequency control or composite output voltage is zero. When the primary and secondary voltages are in phase the voltage in resistor 22 is zero and the voltage in resistor 14 is positive as applied to the output or AFC circuit 23. When the primary and secondary voltages are 45 fully out of phase the potential drop in resistor 22 is equal to twice the drop in the resistor 14 and the automatic frequency or composite output voltage in resistor 14 is negative as applied to the 50 output lead 23.

As indicated by the curve of Fig. 4, this automatic frequency control voltage is substantially linear in the region of exact tuning which in this particular case is assumed to be in the neighborhood of 460 kilocycles. This control potential 55

may obviously be utilized to tune the local oscillator electrically, mechanically or in any other suitable manner, or to simultaneously change the tuning of several signal frequency circuits.

These various relations between the primary 5 and secondary voltages are illustrated by Fig. 2 which indicates the relative values of these voltages at different frequencies and by Fig. 3 which indicates their phase relation at different frequencies, exact tuning in each case being assumed to occur at 460 kilocycles.

Fig. 5 illustrates the application of the invention to a tuned radio frequency receiver including a grounded-rotor multiple-section uni-control tuning capacitor 30. Where these circuits 15 are tuned to the incoming signal frequency, a mechanical frequency control device or an electronic reactance across each tuned circuit would ordinarily be required. Where the adjustable frequency circuits form the intermediate frequency 20 amplifier, the invention may be used to regulate the frequency of the local oscillator. To this end, the substantially frequency independent and frequency responsive control voltages are produced in the resistors 14 and 22 as previously 25 indicated and the resultant of these voltages is applied to the automatic frequency control lead 23 through resistors 32 and 33 which are interconnected with the resistors 14 and 22 to form a bridge network which will be balanced at exact 30 tuning, to give zero frequency control potential. By proper choice of circuit constants, the resistor in the lead 23 of Fig. 1 may be omitted as shown in Fig. 5. In this case, filtering is effected by the resistors 32 and 33.

The arrangement of Fig. 6 differs from the previous modifications in that a separate detector or amplifier 34 is supplied from the secondary of the transformer 12 and a separate diode 35 in place of the diode 13 in Figure 1, coupled through a 40 capacitor 19a to the transformer primary 16 instead of to the secondary, is utilized to produce in a resistor 36 the automatic volume control potential and the frequency independent component of the automatic frequency control potential. 45 This connection has the advantage that somewhat better automatic volume control is secured since the primary is more broadly tuned than the secondary. Fig. 6 also illustrates an arrangement which differs from that of Fig. 1 in 50 that the frequency independent component of the automatic frequency control potential is derived from the automatic volume control lead 27, instead of from the anode end of the filter resistor 28. This assures that no audio frequency voltage 55 will be applied to the diode 20. This potential is then balanced with the vector sum of the rectified primary and secondary voltages by connection through a resistor 24 to the diode 20 output resistor 22, as in Figure 1.

In the circuit of Fig. 7, the automatic volume control potential applied to the lead 27 is amplified by an amplifier 37 interposed between the double diode 38 and the control grids of the controlled tubes such as the tube 11. This requires 65 that the amplifier grid control potential derived from the resistor 14 be positively polarized for the reason that the tube 37 effects a reversal of polarity and the control grids of the controlled tubes such as the tube 11, may be subjected to a 70 negative bias potential. In this case the automatic frequency control potential derived from the resistors 14 and 22 goes from plus to minus as the frequency increases. This would permit the use of an amplifier similar to 37, for amplifying 75

the automatic frequency control potential, if desired, or permit the use of a frequency control means requiring opposite control voltages.

Fig. 8 illustrates an arrangement that is similar to that of Fig. 1, but differs therefrom in that only a portion of the primary voltage is impressed on the cathode of diode 20 by reason of the tapped capacitor connection 31-31. Where very loose coupling is used between primary 16 and secondary 17 of the coupling transformer 12, the primary voltage may be several times as large as that of the secondary. Also, under these conditions, the capacitive reactance of the diode 20 and the resistance of the associated resistors 21-22 may affect the degree of coupling between primary and secondary, and the phase angle between the primary and secondary voltages. By the tapping arrangement shown, the effect of the diode 20 on the transformer is minimized, and 20 the portion of the primary voltage utilized will be approximately the same as that of the secondary, a condition generally desirable for maximum sensitivity to changes in frequency, especially where the phase angle at exact tuning may be some- 25 what less than 90 degrees. Although the voltage divider 31-31 shown is in the capacitive portion of the primary tuned circuit, it is readily apparent that voltage division may be accomplished in the inductive portion of the tuned primary circuit if desired. The circuit of Fig. 8 also differs from that of Fig. 1 in that the frequency independent component of the automatic frequency control potential is derived from the automatic volume control lead 27 instead of the output resistor 14 of the detector 13.

The circuit of Fig. 9 differs from that of Fig. 1 in that the single diodes 13 and 20 are replaced respectively by diode pairs 39-40 and 41-42 so as to secure voltage doubling as disclosed by Schade Patent No. 2,072,278. A further difference is the derivation of the automatic frequency control potential from a bridge circuit formed by the resistors 14 and 22 and a pair of resistors 43-44 to the common terminal of which the lead 23 is connected. The resistors 43 and 44 are not only chosen to attenuate alternating voltages from the lead 23 but are also so proportioned that, at exact tuning, the potential drops of resistors 14 and 22 are exactly balanced. As in the previous arrangements, mistuning results in a control potential which is applied through the lead 23 to a suitable tuning control device such as a local oscillator or the like.

I claim as my invention:

1. An automatic frequency control circuit responsive to an amplitude modulated carrier wave including a transformer provided with primary and secondary windings, a detector connected with said transformer to produce a unidirectional potential component which is substantially independent of the frequency of the impulses supplied to said circuit, means connected with said transformer to produce a unidirectional potential component which varies with change in said frequency, and means providing a series connection between said last-named means and said detector for deriving the resultant of said potential components and the amplitude modulation output.
2. The combination of an automatic frequency control circuit including a transformer having input and output terminals, a detector connected to the output terminals of said transformer, means for deriving from said detector a unidirectional potential which is substantially independ-

ent of frequency within a relatively narrow pass band, means for deriving from the input and output terminals of the transformer a resultant unidirectional potential as the vector sum of input and output potentials which is equal and 5 opposed to said detector unidirectional potential only at exact tuning, and means for combining said unidirectional potentials to provide a controlling potential for said circuit.

3. In a radio signal conveying system, the combination of a coupling transformer having primary and secondary windings tuned to substantially the same signal frequency within a relatively narrow pass band of frequencies, a diode signal rectifier device connected with the 10 secondary winding, means for applying modulated signals through said transformer to said diode rectifier, means for deriving from said rectifier the detected modulation component of said signals, and a resultant direct current potential 15 which is substantially constant with changes in frequency and phase between said primary and secondary windings within said narrow pass band, a second diode rectifier device coupled to the primary and secondary windings of said 20 transformer to receive the vector sum of the potentials in said primary and secondary windings, means for deriving from said second rectifier device a second direct current potential which varies with frequency and the phase relation be- 25 30 between the primary and secondary voltages, a control circuit connecting said potential-deriving means for said rectifiers in series relation to each other, to derive a resultant control potential therefrom.

4. An automatic frequency control circuit including a transformer provided with a primary and a secondary winding, a detector connected with said transformer to produce from one of said windings a unidirectional potential component which is substantially independent of the frequency of the impulses supplied to said circuit within a predetermined relatively narrow pass band, means connected with said primary and secondary windings to produce from both 40 of said windings a unidirectional potential component which varies with change in said frequency within said band, and means for combining said potential components to provide a resultant controlling potential.

5. An automatic frequency control circuit including a transformer provided with tuned primary and secondary windings, a detector connected with one of the windings of said transformer to produce a unidirectional potential component which is substantially independent of the frequency of the impulses supplied to said circuit within a relatively narrow pass band of frequencies, rectifier means connected with both of said windings to produce a unidirectional potential component which varies with change in said frequency from a mean frequency within said pass band, means connected with said detector and rectifier to combine said potential components to produce a third unidirectional potential component which changes in polarity 60 in response to departure of said frequency in different directions from exact tuning to said mean frequency, and circuit means for deriving the resultant of said potential components.

6. The combination of an automatic frequency control circuit including a transformer having input and output terminals, a detector connected to the output terminals of said transformer, means for deriving from said detector a unidirectional potential which is substantially independ- 70 75

ent of frequency within a relatively narrow pass band, means including a mid-tapped tuning capacitor for deriving from said transformer a resultant unidirectional potential as the vector sum of input and output potential which is equal and opposed to said detector unidirectional potential only at exact tuning, and means for combining said unidirectional potentials.

5 7. In a signal conveying system, the combination of a transformer having an input circuit and an output circuit, means for tuning said input and output circuits whereby at resonance to a received signal the potentials therein are substantially 90° out of phase with one another, 10 means for detecting signals in the output circuit of said transformer, additional means for detecting a resultant vector sum of signal potentials in the input and output circuits of said transformer, and means for combining the detected signal output of said detecting means.

15 8. In a signal conveying system, the combination of a transformer having an input circuit and an output circuit, means for tuning said input and output circuits whereby at resonance to a 20 received signal the potentials therein are substantially 90° out of phase with one another, means for detecting signals in the output circuit of said transformer, additional means for detecting a resultant vector sum of signal potentials 25 in the input and output circuits of said transformer, and means including a bridge network

between said first and second-named means for combining the signal output of said detecting means.

9. In a signal receiving system, the combination of a transformer having an input circuit and an output circuit, means for tuning said input and output circuits whereby at resonance to a received signal the potentials therein are substantially 90° out of phase with one another, 5 means for detecting signals in the output circuit of said transformer, additional means including a frequency doubler for detecting a resultant vector sum of signal potentials in the input and output circuits of said transformer, and means for combining the signal output of said detecting 10 means.

10. In a signal conveying system, the combination of a transformer having an input and an output circuit, means for tuning said input and output circuits whereby at resonance to a received signal the potentials therein are substantially 90° out of phase with one another, 15 means for detecting signals in the output circuit of said transformer, additional means including a frequency doubler for detecting a resultant vector 20 sum of signal potentials in the input and output circuits of said transformer, and means including a bridge network for combining the signal output of said detecting means.

WINFIELD R. KOCH.
